PACKAGE FOR FOOD PRODUCTS

John C. Hershey, York, Pa., assignor to J. S. Hershey Baking Company, York, Pa., a corporation of Pennsylvania

Application April 10, 1937, Serial No. 136,063

2 Claims. (Cl. 206—44)

This invention relates to improvements in receptacles of the class suitable for the packaging and display of articles of different kinds, and more especially bakery products such as cakes 5 and the like.

An object of the invention is to provide an improved package for cakes etc., consisting of a transparent covered tray, the tray having sufficient strength and stiffness to support the 10 goods, and having a transparent cover which encloses the contents and renders the same clearly visible for display purposes, the transparent cover being supported from the tray by supporting means in the form of a supplemental 15 tray formed from cardboard, the construction of the package being such that the same may be easily and quickly filled and closed.

Another object of the invention is to provide an improved bakery goods package, which is 20 simple in construction, inexpensive to manufacture, and thoroughly reliable and efficient in use.

With the foregoing and other objects and advantages in view, the invention consists in the preferred construction and arrangement of the 25 several parts which will be hereinafter fully described and claimed.

In the accompanying drawings:—

Figure 1 is a top plan of a package constructed according to the present invention;

Fig. 2 is a bottom plan of the package shown in Fig. 1;

Fig. 3 is an enlarged end view;

Fig. 4 is a vertical transverse section taken on the line 4—4 of Fig. 1;

Fig. 5 is a vertical longitudinal section taken on the line 5—5 of Fig. 1; and

Fig. 6 is a perspective of the cardboard supplemental tray.

The main supporting element of the package 40 comprises a metal pan or tray 11, preferably rectangular in form, and having upstanding side walls 12 and upstanding end walls 13. The pan or tray 11 is formed from suitable sheet metal, and the upper portions of the side and end walls 45 of said tray are reinforced by a suitable stiff wire 14 around which the sheet metal is bent so as to provide a bead 15. The pan or tray 11 is of usual construction, well known in the art, and its purpose is to support the other parts of the 50 package.

Superposed on the bottom of the pan or tray 11, is a supplemental tray 16 formed from a sheet of inexpensive cardboard. The supplemental tray 16 is adapted to lie in the tray 11 and cover the entire bottom thereof, so as to prevent icings

and other material of the cakes, etc., from falling onto or otherwise coming in contact with the bottom of the tray 11.

At both ends, the supplemental tray 16 is formed with upstanding portions 17, and similarly formed upstanding portions 18 project upwardly from the longitudinal side edges of the supplemental tray 16, as shown best in Fig. 6. The side upstanding portions 18 are preferably located midway between the ends of the 10 tray 16, and such portions of the device may have any length desired. On the other hand, as shown in Figs. 3 and 4, the upstanding ends 17 have a length approximately equal to the width of the tray 11, so as to provide suitable end supports 15 for the cover of the device.

The cover 20 is composed of thin flexible or foldable transparent sheet material of any suitable kind, such for example as transparent paper or ordinary fibre paper treated in any suitable or well known manner to render it transparent, or "Cellophane" or any of the other well known thin transparent flexible sheet cellulose products obtained from viscose.

Material for the cover should have sufficient 25 width to extend from a suitable point under the bottom of the pan or tray 11, upwardly over one of the longitudinal sides of the device, across the top, then downwardly of the opposite longitudinal side, and from thence to a suitable point 30 under the bottom of the pan or tray 11.

When the cover 20 is thus wrapped around the device, its free longitudinal edges on the underneath of the pan or tray 11 are secured together by means of a plurality of strips of adhesive tape 35 23, as shown best in Fig. 2. These strips of tape 23 may also be applied to the exposed surface of the underside of the tray 11, so as to more rigidly and securely fasten the adjacent longitudinal edges of the cover to the tray. 40

The sheet of material from which the cover 20 is made is longer than the length of the tray 11, so that the ends of the cover can be folded downwardly over the upstanding ends 18 of the supplemental tray 16, as shown at 25, Figs. 3 and 45 5. The portions of the cover which project outwardly from the ends of the longitudinal sides of the package are also adapted to be folded inwardly towards the ends 18, as indicated at 26, Fig. 3. 50

The ends of cover 20 are then adapted to be securely fastened by means of a plurality of strips of adhesive tape 27. These strips of tape may extend from the top of the package and around the ends thereof, and terminate under 55

the bottom of the pan or tray 11, as shown in Figs. 1, 2, 3 and 5.

If so desired the adhesive tape heretofore described may be formed from strips of material similar to the material used for the cover 20, to which material a suitable adhesive is applied.

The package is adapted to be formed by first placing a cardboard supplemental tray 16 in position in a metal pan or tray 11, the portions 17 and 18 of the supplemental tray 16 being first bent upwardly, as shown in Fig. 6. The cakes or other bakery products, indicated by the broken lines at 30, are now placed on the supplemental tray 16, after which the cover 20 is wrapped around the device and secured thereto in the manner heretofore described. By utilizing inexpensive cardboard for the supplemental tray 16 and thin sheets of transparent wrapping material for the cover 20, the cost of the package is very small, being at the present time two or three cents for a package two feet long, about one foot in width and four inches in height. The portions 17 and 18 of the supplemental tray 16 should extend upwardly a distance sufficiently high to maintain the portion of the cover 20 which constitutes the top of the package in spaced relation, say approximately one-half inch, above the top of the cakes, etc., 30 within the package.

30 By providing only two opposed upstanding side members 18 of the supplemental tray 16, sufficient supporting means will be provided intermediate the ends of the package for retaining the cover 20 in position above the contents of the package, and due to the transparency of the cover material, obviously the contents of the package will be displayed to a considerable extent.

Having thus described my invention, what I claim is:—

1. A container for bakery products and the like, comprising a pan having a relatively short upstanding wall of uniform height, a cardboard tray mounted on the bottom of said pan so as to cover the same and having upstanding end portions and upstanding side portions integral therewith, said upstanding end and side portions projecting upwardly above said wall, said upstanding side portions of the cardboard being of less length than the length of the side wall of said pan, a wrapper of sheet material having its ends folded downwardly to enclose the upstanding ends of said cardboard tray and its longitudinal edges folded under the bottom of said pan, said wrapper being supported in spaced relation above said pan by said upstanding portions of said tray and strips of adhesive tape for securing the free edges of said wrapper to said pan 20 and to the ends of said tray.

2. A container for bakery products and the like, comprising a sheet metal pan having a relatively short upstanding wall, a cardboard sheet superposed upon the bottom of said pan and having an area approximately the same as the area of the bottom of the pan so as to cover the bottom of said pan, end portions integrally formed with said cardboard sheet and projecting upwardly above said wall of the pan, relatively narrow diametrically disposed side portions integrally formed with said cardboard sheet and projecting upwardly above said pan to a height approximately the same as the height of said end portions, and a cover of sheet material 35 wrapping said pan and said cardboard sheet and supported in spaced relation above said pan by said upstanding portions of said cardboard sheet.

JOHN C. HERSHEY.
